CLAIM

The ornamental design for a solar palace lantern, as shown and described.

DESCRIPTION

FIG. 1 is a top, front and right side perspective view of a solar palace lantern, showing my new design;

FIG. 2 is a top, rear and right side perspective view;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the drawings illustrate the portions of the solar palace lantern, which form no part of the claimed design.
